ABSORPTION REFRIGERATION HOME APPLIANCE

Benjamin A. Phillips, Benton Harbor, Mich., assignor to Whirlpool Corporation, a corporation of Delaware
Filed June 13, 1960, Ser. No. 35,720
5 Claims. (Cl. 62—485)

This invention relates to refrigerators and in particular to means for circulating air in an absorption refrigerator.

In an absorption refrigerator, the energy input to the refrigeration system is in the form of heat delivered to the refrigerant in a boiler in heat exchange relationship with a fuel burner. Conventionally, the burner comprises a fluid fuel burner to which air must be supplied to support combustion thereof. Such absorption refrigerators further include, as elements of the refrigeration system, elements such as a condenser, an absorber, a rectifier, and a weak liquid precooler from which it is necessary to dissipate heat during the refrigeration cycle. Thus, it is desirable to provide a flow of air in heat transfer relationship with such elements.

The present invention is concerned with a new and improved means for providing such combustion and cooling air. A prime feature of the invention is, therefore, the provision of a new and improved air flow means for use in an absorption refrigerator having a burner and system components from which heat is to be dissipated.

Another feature of the invention is the provision of such air flow means including a first air passage associated with the burner for providing combustion air thereto and terminating at a preselected space, means defining a second air passage associated with the system components for passing air in heat transfer relationship therewith and terminating at the space, and air moving means in the space for moving air concurrently through each of the air passages.

A further feature of the invention is the provision of such air flow means arranged for automatic proportioning of the total air flow in the respective air passages for proper operation of the refrigerator.

A further feature of the invention is the provision of such air flow means further arranged for improved exhausting by the air moving means of the air moved thereby.

Other features and advantages will be apparent from the following description taken in connection with the accompanying drawing wherein:

FIGURE 1 is a rear elevation of an absorption refrigerator provided with air flow means embodying the invention, a portion of the refrigerator back wall being broken away.

FIGURE 2 is an enlarged, broken horizontal section thereof taken substantially along the line 2—2 of FIGURE 1.

In the exemplary embodiment of the invention as disclosed in the drawing, an absorption refrigerator generally designated 10 is provided with a suitable cabinet 11. Extending rearwardly from the back wall 12 of the cabinet is a frame 13 carrying at its rearward end a back panel 14 defining therebetween a long vertical space 15. Spaced above the bottom of rear wall 12 and extending horizontally forwardly therefrom is a bottom wall 16. A vertical divider 37 extends downwardly from bottom wall 16 and perpendicularly to rear wall 12 to divide the space below bottom wall 16 into a first chamber 17 and a second chamber 18 extending from rear wall 12 forwardly to front wall 19 of cabinet 11.

Within chamber 17 is provided a burner 20, a boiler 21 for holding refrigerant in heat transfer relationship

2

with the flame of burner 20, and an exhaust flue 22 for exhausting the products of combustion from the burner. A portion of burner 20, boiler 21, and flue 22 are carried within an insulated housing 23 which extends through an opening 24 in rear wall 12 whereby air is delivered to burner 20 from chamber 17 and the products of combustion are delivered from flue 22 to space 15.

The elements of the refrigeration system from which it is desired to dissipate heat during the operation of the refrigerator are disposed in space 15, as best seen in FIGURE 1. More specifically, a finned condenser 25 is mounted at the top of space 15 for delivery through a conduit 26 to the refrigerator evaporator (not shown) forwardly of rear wall 12. Rectifier 26a is in the line from the boiler 21 to condenser 25. A gas heat exchanger 27 receives the refrigerant from the evaporator and delivers it to the absorber pot 28 and associated finned absorber 29. A finned heat exchanger 30 is connected between absorber pot 28 and boiler 21 for precooling the weak liquid delivered from the boiler to the absorber pot. Thus, within space 15 are mounted four refrigeration system elements from which heat is to be dissipated, namely the condenser 25, rectifier 26a, the absorber 29, and the precooler 30.

A flow of air to burner 20 for supporting combustion therein, an exhausting of the products of combustion from burner 20 and through flue 22, and a movement of air in heat transfer relationship with refrigeration system elements 25, 26a, 29 and 30 are concurrently provided in refrigerator 10 by an air moving means herein comprising a conventional propeller fan 31 driven by an electric motor 32. Fan 31 is disposed in an opening 33 in rear wall 12 below bottom wall 16 and is arranged to deliver air from the lower portion of space 15 through chamber 18 and outwardly from chamber 18 through an opening 34 in the front wall 19 of the refrigerator cabinet 11. Opening 34 extends horizontally substantially fully across the lower end of wall 19 thereby further defining an inlet to chamber 17 for delivery of combustion supporting air to the burner 20. The cooling air is admitted to chamber 15 through a suitable opening or grill 35 extending horizontally across space 15 at the upper end thereof.

In operation, fan 31 draws air through a portion of front opening 34, through chamber 17, to burner 20 wherein it supports combustion of the fuel, through flue 22 in the form of products of combustion, and through the lower portion of space 15 for delivery through chamber 18 and front opening 34 outwardly from the cabinet 11. Concurrently, the fan draws air downwardly through opening 35, in heat exchange relationship with condenser 25, rectifier 26a, absorber 29, and pre-cooler 30, and to the lower portion of space 15 for delivery through chamber 18 and front opening 34 outwardly from the cabinet.

The amount of air drawn downwardly through space 15 for cooling elements 25, 26a, 29 and 30 is proportioned automatically by the cross sectional areas and the corresponding pressure drop characteristics of the burner 20, generator flue 22 and flue baffle 38, and the portions of the refrigeration apparatus in the air flow path downwardly through space 15 so that approximately 98% to 99% of the air discharged through front opening 34 by fan 31 comprises the cooling air moved downwardly through space 15. The amount of air drawn through burner 20 assures full combustion of the fuel therein permitting delivery of the products of combustion to the space in front of the refrigerator without harmful effects to any occupants thereof.

Having described my invention as related to the embodiment shown in the accompanying drawing, it is my intention that the invention be not limited by any of the details of description, unless otherwise specified, but

rather be construed broadly within its spirit and scope as set out in the accompanying claims.

The embodiment of the invention in which an exclusive property or privilege is claimed is defined as follows:

1. In an absorption refrigerator having a cabinet having a bottom portion, a burner, and system components from which heat is to be dissipated, air flow means comprising: means defining a first air passage associated with the burner for providing combustion air thereto, said first air passage terminating at a preselected space; means defining a second air passage associated with said system components for passing air in heat transfer relationship therewith, said second air passage terminating at said space; means defining a third, common air passage leading from said space outwardly from the bottom portion of the cabinet; and air moving means in said space for positively moving air concurrently through each of said air passages.

2. In an absorption refrigerator having a cabinet having a bottom portion, a burner, and system components from which heat is to be dissipated, air flow means comprising: means defining a first air passage associated with the burner for providing combustion air thereto, said first air passage terminating at a preselected space; means defining a second air passage associated with said system components for passing air in heat transfer relationship therewith, said second air passage terminating at said space; means defining a third air passage leading from said space for delivery of the air from said first and second passages to an exhaust outlet in the bottom portion of the cabinet; and air moving means in said space for positively moving air concurrently through each of said air passages and outwardly through said outlet.

3. In an absorption refrigerator having a burner, and system components from which heat is to be dissipated, air flow means comprising: means defining a first air pas-

sage associated with the burner for providing combustion air thereto, said first air passage terminating at a preselected space; means defining a second air passage associated with said system components for passing air in heat transfer relationship therewith, said second air passage terminating at said space and having a cross section co-ordinated with the air flow impeding characteristic of the burner and the air flow impeding characteristic of the system components preselected to pass approximately 98% of the total air passed through said passages; and air moving means in said space for moving air concurrently through each of said air passages.

4. In an absorption refrigerator having a cabinet including top and bottom portions, a burner and system components from which heat is to be dissipated, air flow means comprising: means defining a first generally horizontally extending air passage in the bottom portion of the cabinet and having an inlet end associated with the burner for providing combustion air thereto, said first air passage terminating at the end opposite said inlet in a preselected space; means defining a second, generally vertical air passage extending between said top and bottom portions and associated with said system components for passing air in heat transfer relationship therewith, said second air passage terminating in said space, said space being at the lower end of said second air passage; and air moving means in said space for moving air concurrently through each of said air passages.

5. The air flow means of claim 4 including means defining a third air passage leading from said space to an exhaust outlet adjacent the inlet of the first air passage.
